UNITED STATES PATENT OFFICE.

CLYDE E. SWICK, OF SAN FRANCISCO, CALIFORNIA, ASSIGNOR, BY MESNE ASSIGNMENTS, TO HAWLEY PULP AND PAPER COMPANY, A CORPORATION OF OREGON.

PAPER-INTERFOLDING MACHINE.

1,302,240.

Specification of Letters Patent. Patented Apr. 29, 1919.

Application filed October 8, 1915. Serial No. 54,828.

To all whom it may concern:

Be it known that I, CLYDE E. SWICK, of San Francisco, in the county of San Francisco, and in the State of California, have 5 invented a certain new and useful Improvement in Paper-Interfolding Machines, and do hereby declare that the following is a full, clear, and exact description thereof.

My invention relates particularly to a machine designed to produce folded sheets of paper, as for example, for use as towels, etc., either craped or plain.

The object of my invention is to provide a machine of this kind which is adapted to 15 produce packs of folded paper sheets, said packs being so arranged that when one of the lower sheets of the pack is pulled downwardly, it is readily removed from the pack and, at the same time, withdraws the free 20 end of the next succeeding sheet of paper so that said next succeeding sheet may be readily withdrawn in a similar manner from the lower end of the pack. Such packs of folded sheets are customarily retained in a 25 box having an open slot at its bottom so arranged that the free edge of the lowermost sheet projects through the slot so as to permit the removal of the sheets, one after another, in the manner above described. The 30 box or means used for retaining the pack of folded sheets for use, however, forms no part of my invention herein. A further object of my invention is to provide a machine of the above character which is adapted to 35 produce packs of folded paper sheets from paper rolls. Another object of my invention is to provide a machine of the above character, which is so arranged as to operate continuously. Further objects of my 40 invention will appear from the detailed description thereof appearing hereinafter.

While my invention is capable of embodiment in many different forms for the purpose of illustration I have shown only one 45 form thereof in the accompanying drawings, in which,

Figure 1 is a side elevation of a machine made in accordance with my invention;

Fig. 2 is a vertical section of the same 50 taken parallel to Fig. 1;

Fig. 3 is a rear elevation of the same;

Fig. 4 is a side elevation partly in section 55 of one of the interfolding cylinders;

Fig. 5 is a vertical section of the same 60 taken on line 5-5 of Fig. 4;

Fig. 6 is a vertical section of one of the male cutting rolls;

Fig. 7 is a side elevation partly in section 65 of one of the female cutting rolls;

Fig. 8 is a vertical section of one of the 60 male cutting rolls taken on line 8-8 of Fig. 6;

Fig. 9 is a similar section of one of the 65 female cutting rolls taken on line 9-9 of Fig. 7;

Fig. 10 is an enlarged detail partly in section showing the printing devices;

Fig. 11 is an end elevation of the same; and

Fig. 12 is an enlarged detail of a portion 70 of one of the interfolding cylinders showing the spring means for operating the grippers.

In the drawings I have shown a paper interfolding machine having two lower side frames 1, adapted to be connected together 75 and retained in place by connecting rods 2. Upon the tops of the lower side frames 1, there are supported two upper side frames 3. The upper side frames 3 are arranged to receive a main driving shaft 5 having a 80 tight pulley 6, and a loose pulley 7 thereon, adapted to be connected with any suitable source of power. Upon the extreme end of this shaft there is located a hand-wheel 8, which may serve, when desired, as 85 a wheel for imparting a small degree of movement to the main shaft 5 in threading the paper into the machine at the start. This main shaft 5 constitutes the shaft for supporting a female cutting cylinder 9, 90 which cooperates with a male cutting cylinder 10, located adjacent thereof. On the shaft 5 of the female cutting cylinder 9 there is, furthermore, a gear 11, which meshes with a gear 12 located on a shaft 13 supporting 95 the male cutting cylinder 10. In mesh with the gear 11 there is also a gear 14 on a shaft 15 which carries a paper feeding cylinder 16, against which there rests a tension roll 17, located on arms 18, supported upon a shaft 19 around which there are located 100 springs 20 for pressing the tension rolls 17 against the surface of the feeding roll 16. The tension roll 17 is adapted to receive a paper web A which may be either craped or plain. The gear 11, furthermore, meshes 105 with a further gear 21 on a shaft 22, which carries an interfolding cylinder 23, which gear 21 in turn meshes with a gear 24 on a shaft 25 carrying a rotary tumbler cylinder 110

der gear 26. The same gear 21 also meshes with a gear 27 on a shaft 28, which shaft has a smaller gear 29, meshing with a gear 30 on a shaft 31, carrying a roll 32 to receive a pair of conveying tapes 33 passing therefrom to a roll 34, which also receives a further pair of conveying tapes 35. The parts thus far described are located on one side of the machine, the parts on the other side of the machine being constructed in the same manner, except that the last mentioned parts are driven from the main driving shaft 5 already described, and contain, in addition, some further parts to be described hereinafter. These parts are driven in the following manner: The gear 21 meshes with a gear 36 on a shaft 37 carrying another paper interfolding roll 38. This gear 36 meshes in turn with a gear 39 on a shaft 40, carrying a further rotary tumbler cylinder gear 41. The gear 36, furthermore, meshes with a gear 42 on a shaft 43 carrying another female cutting roll 44, said gear 42 in turn meshing with a gear 45 on a shaft 46 carrying a male cutting roll 47. Furthermore, the same gear 42 meshes with a gear 48 on a shaft 49, carrying a feeding roll 50, and said gear 48 meshes with a gear 51 on a shaft 52, carrying a printing bed cylinder 53. The gear 51 in turn meshes with a gear 54 on a shaft 55, carrying a printing roll 56, to mark the web of paper at measured intervals, so as to provide paper packs of equal size, which coöperates with an ink-rolling roll 57 on a shaft 58 carried in an arm 59 supported upon a rod 60, passing through the upper side frames 3. In contact with the feeding roll 50 there is also a tension roll 61 supported upon arms 62 carried by a shaft 63, having springs 64 to press the roll 61 against the surface of the feeding cylinder 50. A paper web B is fed into this side of the machine over the shaft 63, and then between the rolls 53 and 56. From the above, it will be seen, that the machine is provided on the two sides of the machine with duplicate tension rolls 17 and 61, feeding rolls 16 and 50, male cutting cylinders 10 and 47, female cutting cylinders 9 and 44, paper interfolding rolls 23 and 38, and rotary tumbler cylinder gears 26 and 41.

The paper web A, being fed into the machine between the tension rolls 17 and the feeding rolls 16, passes around the feeding rolls 16 and thence around the female cutting roll 9. The female cutting roll 9 is provided on opposite sides with longitudinal troughs 65, in which there is supported a pair of bars 66 and 67 spaced apart by sleeves 68 through which pass screw-threaded holes 69 for receiving adjusting bolts 70, having nuts 71 on their ends. The bars 66 and 67 are held in place by means of screws 72, which pass through slots 73 in

cylinder 9, the adjustment of the bars 66 and 67 being obtained by first loosening the screws 72 and then adjusting the bolts 70, the heads of which rest against the side of the trough 65. The bars 66 and 67 are so arranged as to leave a cutting slot 74 between the same. These slots 74 are designed to register with knives 75 carried on brackets or bars 76, located on opposite sides of the male cutting cylinder 10. The brackets or bars 76 are provided with screw-threaded openings 77, to receive adjusting screws 78 adapted to fit within recesses 79 on the opposite sides of the cylinder 10, on which the bars 76 are located. Furthermore, these bars or brackets 76 are arranged near their ends with slots 80 to receive screws 81, which retain the bars 76 in their adjusted positions. These bars 76 are, furthermore, provided adjacent to the knives 75 with strippers 81^a, having extensions 82 resting upon the top of springs 83, located on said bars 76 and the strippers 81^a are arranged so that their movement is limited by screws 84 screw-threaded into openings in the sides 90 of the bars 76. On the opposite sides of the knives 75 to the strippers 81^a, there are located soft rubber paper holding strips 86. It will be noted that these knives 75 are provided with notches 87 and serrated edges 88^a 95 so that the paper web when it passes between the rolls 9 and 10, is cut, except for the four connecting portions produced by the notches 87. From this point the web of paper A passes around the female cutting cylinder 9 until it reaches the paper interfolding cylinder 23. When it reaches this point the notches produced in the web A receive one of the folding blades 88 of which there are two located on opposite sides of 105 the cylinder 23. Each of these folding blades 88 is supported upon a bracket 89 located in a trough 90 (Fig. 2) in the face of the cylinder 23, and is adapted to be adjusted by screws 91 which pass into screw-threaded holes on opposite sides of the bracket 89. Screws 93 passing through slots 94 in the ends of the bracket 89 hold the bracket in its adjusted position. The bracket 89 is provided at intervals with slots 115 95 which correspond in position to the connecting holes produced by the notches 87. It will be noted that the blade 88 is broken at intervals and extends between the several slots 95 and between the two end slots 120 94, and the ends of the bracket 89, said blade 88 being held in position by a plate 96, said plate 96, blade 88 and the bracket 89 being provided with holes 97 to receive screws 98 screw-threaded into the bracket 125 89. In the slots 95, knife-edged tongues 99 are arranged to reciprocate, said tongues being carried upon bars 100, to which they are attached by screws 101. The bars 100 are arranged to move in a radial direction in 130

slots 102 in the cylinder 23, and below the troughs 90, and they are adapted to be retained normally at the bottom of said recesses 102 by springs 103 located in recesses 104 in the bars 100. These tongues 99 are adapted to be moved by lever arms 105 carried upon shafts 106 and adapted to rest beneath the bars 100. Secured on the shafts 106 there are located, furthermore, lever arms 107 (Figs. 2 and 3) having rollers 108, which bear upon the outside of a cam 109 located on the shaft 22. The contour of the cam 109 is such that the knife-edged tongues 99 are flush with the surface of the cylinder at the position of the cylinder 23 where the tongues 99 come adjacent to the cylinder 9, but thereafter, the tongues 99 are moved outwardly gradually by an inclined portion 110 (Fig. 2) on the cam 109 until they are flush with the outer edge of the blade 88. Thereafter, the cam 109 is provided with a sharp rise 111, so as to extend the tongues 99 above the surface of the blade 88, to sever the connecting portions in the paper web produced by the notches 87, and to completely sever the paper sheet from the body of the paper web being fed into the machine. As previously stated, the two paper interfolding cylinders 23 and 38 are constructed exactly alike, but they are positioned in such a manner that the folding blades 99 on one cylinder register with the gripping means on the other cylinder, the gripping means being positioned 90° away from the blades 88 on each of the paper interfolding cylinders. The gripping means is comprised of stationary gripping jaws 113 held in place on the cylinder by screws 114 and spring-pressed rotary gripping jaw 115, which are located on a shaft 116 to which there is attached an arm 117 (Fig. 2) having a roller 118, which is arranged to run within a cam 119, carried by the shaft 22.

The other web of paper B is fed into the machine and reaches the corresponding paper interfolding cylinder 38 in the same manner and through the same series of operations as in the case of the paper web A except in the following respects: The paper web B is fed into the machine between the printing bed cylinder 53 and the printing cylinder 56, the purpose of said cylinders being to print a mark upon the paper web B in such a way as to provide 150 interfolded paper sheets in each package when the packages are severed opposite the marks provided by the two cylinders referred to, the mark being so located that it overlies one of the folded edges in the packs of folded sheets so as to be readily seen by the operator, and so as to permit severance of the packs at that point by the operator, as the folded sheets pass out of the machine. The printing of the marks upon the web of paper at the intervals above referred to,

is accomplished in the following manner. The gear 51 on the shaft 52 is provided with seventy-four teeth, while the gear 54 on the shaft 55 is provided with seventy-five teeth, so that the teeth on gear 54 will gain one tooth at every revolution thereof, and, in other words, a given point on the gear 54 will come opposite to the same point on the gear 51 at each seventy-five revolutions of the gear 51, the marks being designed to measure off a distance to provide each pack with seventy-five double sheets, that is to say, 150 single sheets. The gear 51 is provided with a stationary plunger 120, to which it is held by a screw 121 and a pin 122. The gear 54, on the other hand, is provided with a movable plunger 123, having a tooth 124, projecting upwardly opposite one of the recesses between two adjacent teeth in this gear, and this movable plunger 123 has, furthermore, a longitudinal slot 125, which communicates with one end of a lever 126 located on a clamp 127 secured to the shaft 55 in such a manner that the other end of the lever 126 communicates with a printing marker 128 in a slot 129 in the roller 56, which marker 128 is adapted to be normally retracted by a spring 130, and arranged to be removably held in place by a plate 131 secured to the roll 56 by screws 132. In the rotation of the printing cylinder 56, ink is supplied to the marker 128 from the inking cylinder 57, which is a composition roll of the usual kind provided for inking type. From this point the web of paper passes over the top of the feeding cylinder 50, then between the female and male cutting cylinders 44 and 47, and then finally on to the paper interfolding cylinder 38. The two webs of paper A and B located on the interfolding cylinders 23 and 38 respectively, are now interfolded by said cylinders owing to the fact that the blades 88 and the knife-edged tongues 99 project the webs of paper into the gripping jaws 113 and 115, which are maintained open by the cam which operates the same at the point where the blade 88 and the knife-edged tongues 99 come opposite said gripping jaws. Immediately after this, the gripping jaws 113 and 115 are brought together to fold one web between two partially severed portions and the other web at a partially severed portion, by the action of the springs actuating the jaws and owing to the release of the roller 118 by the cam 119 co-operating with the same, and immediately thereafter, the knife-edged tongues 99 make a sharp movement toward the gripping jaws 113 and 115 by the sudden rise 111 in the cam 109, thereby severing the connecting portions of one web left by the notches 87, and thus entirely severing one sheet of paper from the web of paper to which it was attached and interfolding the other web therewith. Further rotation of

the interfolding rolls 23 and 38 thereafter removes the blade 88 and the tongues 99 from the gripping jaws 113 and 115. The folded web of paper carrying the severed sheet in the fold is now carried around by one of the interfolding cylinders, as for example, the cylinder 23 until it reaches a point on the underside of the cylinder, directly below the center of the cylinder, but a short distance before the center of the cylinder is reached, at which point the rotary gripping jaw 115, holding the same, is released through the action of the cam 119. At the same time, stripping arms 132^a, which normally run in grooves 133 on the cylinder 23, and which are pivotally supported upon a shaft 134 operated by an arm 135, having a roller 136, which runs on a cam 137 (Fig. 3) on the shaft 22, are moved outwardly by springs 138 on the shaft 134, thus removing the folded paper from between the jaws 113 and 115, and pressing the same down upon a stationary tumbler 139. The fold of paper which is now supported between the stripper arms 132^a and the tumbler 139 is removed from between the same by a revolving tumbler bar 140 located on a shaft 141, which has a gear 142 in mesh with the gear 26, so as to rotate the same at the proper speed to remove the folds from between the stripper blades 132^a and the stationary tumbler 139 at the proper intervals. The same action takes place in the same way at the other side of the machine where parts constructed exactly the same are provided for operating stripper blades 132^a in connection with a stationary tumbler 139, and co-operating with a rotary tumbler 140 located on a shaft 146 having a gear 147 meshing with gear 41 on a shaft 40, which shaft 40 has a further gear 39, meshing with the gear 36. The folded webs of paper are thus fed downwardly in zigzag shape to the upper surface of the conveying tapes 33, so that said webs are thus continuously fed out of the machine, and on to the conveying tapes 35, at which point the packs of folded sheets containing 150 single sheets or 75 double sheets may be severed by the operator at the points indicated thereon by the marks which have been applied by the printing devices on the machine. These packs of paper, as suggested above, are now ready for use, as for example, by insertion in a box containing a slot at its lower surface in such a manner that the free edge of the lowermost sheet of paper projects out through the slot. When a sheet of paper is to be used, it is merely necessary to pull the free projecting edge of the lowermost sheet of paper, which withdraws said sheet from the pack, while, at the same time, pulling out from the slot the free edge of the next sheet of paper contained in the pack. The sheets of paper in the pack may then be successively removed from the pack,

until the entire pack of paper sheets has been used. As stated above, these packs of paper sheets may be of plain or craped paper, and they may be used for any desired purpose, but they are especially useful as paper towels.

While I have described my invention above in detail, I wish it to be understood that many changes may be made therein without departing from the spirit of my invention.

I claim:

1. In a paper web interfolding machine, cutting elements having means for partially severing webs of paper at alternate points along the lengths of said webs, and means for folding said sheets at each of the partially severed portions and completely severing the web which has been partially severed at that point. 85

2. In a device of the class described, cutters for partially severing webs of paper, means for folding said webs, and additional cutting elements for completely severing said webs at the points which previously had been partially severed. 90

3. In a device of the class described, a pair of paper web folding rolls each having gripping jaws and a folding element respectively engaging the folding element and gripping jaws of the other roll, a cutting tongue mounted on each roll, and means for projecting said tongue between the gripping jaws of the other element to cut the web at that point. 100

4. In a paper web interfolding machine, rolls having means for partially severing webs of paper at alternate points along the lengths of said webs, and means for folding said sheets at each of the partially severed portions and completely severing the web which has been partially severed at that point. 105

5. In combination, feeding apparatus for feeding paper and interfolding devices connected thereto for producing interfolded sheets of paper with the two adjacent edges of two adjacent sheets located in the fold of another sheet, comprising an interfolding cylinder and devices for partially severing sheets from a web of paper and thereafter feeding the web on to the inner folding cylinder. 115

6. In combination, feeding apparatus for feeding a continuous web of paper and interfolding devices connected thereto for producing interfolded sheets of paper with the two adjacent edges of two adjacent sheets located in the fold of another sheet, comprising an interfolding cylinder and devices for partially severing sheets from a web of paper and thereafter feeding the web on to the interfolding cylinder. 120

7. In combination, feeding apparatus for feeding paper and interfolding devices con- 125

5 nected thereto for producing continuously interfolded sheets of paper with the two adjacent edges of two adjacent sheets located in the fold of another sheet, comprising an interfolding cylinder and devices for partially severing sheets from a web of paper and thereafter feeding the web on to the interfolding cylinder.

8. In combination, feeding apparatus for feeding a continuous web of paper and interfolding devices connected thereto for producing continuously interfolded sheets of paper with the two adjacent edges of two adjacent sheets located in the fold of another sheet, comprising an interfolding cylinder and devices for partially severing sheets from a web of paper and thereafter feeding the web on to the interfolding cylinder.

9. In combination, feeding apparatus for
20 feeding paper and interfolding devices con-
nected thereto for producing interfolded
layers of paper, comprising an interfolding
cylinder and devices for partially severing
sheets from a web of paper and thereafter
25 feeding the web on to the interfolding cyl-
inder, said devices comprising a female cutting
cylinder and a male cutting cylinder,
the latter having a rubber strip, a knife and
a stripper.

30 10. In combination, feeding apparatus for feeding a continuous web of paper and interfolding devices connected thereto for producing interfolded layers of paper, comprising an interfolding cylinder and devices
35 for partially severing sheets from a web of paper and thereafter feeding the web on to the interfolding cylinder, said devices comprising a female cutting cylinder and a male cutting cylinder, the latter having a
40 rubber strip, a knife and a stripper.

45 13. In combination, feeding apparatus for feeding paper and interfolding devices connected thereto for producing continuously interfolded layers of paper, comprising an interfolding cylinder and devices for partially severing sheets from a web of paper and thereafter feeding the web on to the interfolding cylinder, said devices comprising a female cutting cylinder and a male cutting cylinder, the latter having a rubber strip, a knife and a stripper.

55 strip, a knife and a stripper.

12. In combination, feeding apparatus for feeding a continuous web of paper and interfolding devices connected thereto for producing continuously interfolded sheets of paper, comprising an interfolding cylinder and devices for partially severing sheets from a web of paper and thereafter feeding the web on to the interfolding cylinder, said devices comprising a female cutting cylinder and a male cutting cylinder, the latter having a rubber strip, a knife and a stripper,

13. In combination, feeding apparatus for feeding paper and interfolding devices connected thereto for producing interfolded

sheets of paper with the two adjacent edges of two adjacent sheets located in the fold of another sheet, comprising an interfolding cylinder and devices for partially severing sheets from a web of paper and thereafter 70 feeding the web on to the interfolding cylinder, said devices comprising a female cutting cylinder and a male cutting cylinder, the latter having a rubber strip, a knife and a stripper. 75

14. In combination, feeding apparatus for feeding a continuous web of paper and interfolding devices connected thereto for producing interfolded sheets of paper with the two adjacent edges of two adjacent sheets located in the fold of another sheet, comprising an interfolding cylinder and devices for partially severing sheets from a web of paper and thereafter feeding the web on to the interfolding cylinder, said devices comprising a female cutting cylinder and a male cutting cylinder, the latter having a rubber strip, a knife and a stripper. 80
85

15. In combination, feeding apparatus for feeding paper and interfolding devices connected thereto for producing continuously interfolded sheets of paper with the two adjacent edges of two adjacent sheets located in the fold of another sheet, comprising an interfolding cylinder and devices for partially severing sheets from a web of paper and thereafter feeding the web on to the interfolding cylinder, said devices comprising a female cutting cylinder and a male cutting cylinder, the latter having a rubber strip, a knife and a stripper. 95 100

16. In combination, feeding apparatus for feeding a continuous web of paper and inter-folding devices connected thereto for producing continuously interfolded sheets of paper with the two adjacent edges of two adjacent sheets located in the fold of another sheet, comprising an interfolding cylinder and devices for partially severing sheets from a web of paper and thereafter feeding the web on to the interfolding cylinder, said devices comprising a female cutting cylinder and a male cutting cylinder, the latter having a rubber strip, a knife and a stripper. 115 110 115

17. In combination, feeding apparatus for feeding paper and interfolding devices connected thereto for producing interfolded sheets of paper with the two adjacent edges of two adjacent sheets located in the fold of another sheet, comprising a pair of co-operating interfolding cylinders, each having folding blades and gripping jaws, and devices for partially severing sheets from a web of paper and thereafter feeding the web on to the interfolding cylinders. 125 120

18. In combination, feeding apparatus for feeding a continuous web of paper and interfolding devices connected thereto for producing interfolded sheets of paper with the 130

- for feeding a continuous web of paper and interlocking devices connected thereto for producing interlocked sheets of paper, comprising a pair of coöperating interlocking cylinders, each having interrupted folding blades with movable cutting tongues located in the interruptions in the folding blades and gripping jaws, and devices for partially severing sheets from a web of paper and thereafter feeding the web on to the interlocking cylinders, said devices comprising a female cutting cylinder and a male cutting cylinder, the latter having a rubber strip, a knife and a stripper. 5

10 39. In combination, feeding apparatus for feeding paper and interlocking devices connected thereto for producing continuously interlocked sheets of paper, comprising a pair of coöperating interlocking cylinders, each having interrupted folding blades with movable cutting tongues located in the interruptions in the folding blades and gripping jaws, and devices for partially severing sheets from a web of paper and thereafter feeding the web on to the interlocking cylinders, said devices comprising a female cutting cylinder and a male cutting cylinder, the latter having a rubber strip, a knife and a stripper. 15

20 40. In combination, feeding apparatus for feeding a continuous web of paper and interlocking devices connected thereto for producing continuously interlocked sheets of paper, comprising a pair of coöperating interlocking cylinders, each having interrupted folding blades with movable cutting tongues located in the interruptions in the folding blades and gripping jaws, and devices for partially severing sheets from a web of paper and thereafter feeding the web on to the interlocking cylinders, said devices comprising a female cutting cylinder and a male cutting cylinder, the latter having a rubber strip, a knife and a stripper. 25

30 41. In combination, feeding apparatus for feeding a continuous web of paper and interlocking devices connected thereto for producing continuously interlocked sheets of paper, comprising a pair of coöperating interlocking cylinders, each having interrupted folding blades with movable cutting tongues located in the interruptions in the folding blades and gripping jaws, and devices for partially severing sheets from a web of paper and thereafter feeding the web on to the interlocking cylinders, said devices comprising a female cutting cylinder and a male cutting cylinder, the latter having a rubber strip, a knife and a stripper. 35

40 42. In combination, feeding apparatus for feeding a continuous web of paper and interlocking devices connected thereto for producing continuously interlocked sheets of paper, comprising a pair of coöperating interlocking cylinders, each having interrupted folding blades with movable cutting tongues located in the interruptions in the folding blades and gripping jaws, and devices for partially severing sheets from a web of paper and thereafter feeding the web on to the interlocking cylinders, said devices comprising a female cutting cylinder and a male cutting cylinder, the latter having a rubber strip, a knife and a stripper. 45

45 43. In combination, feeding apparatus for feeding paper and interlocking devices connected thereto for producing continuously interlocked sheets of paper with the two adjacent edges of two adjacent sheets located in the fold of another sheet, comprising a pair of coöperating interlocking cylinders, each having interrupted folding blades with movable cutting tongues located in the interruptions in the folding blades and gripping jaws, and devices for partially severing sheets from a web of paper and thereafter feeding the web on to the interlocking cylinders, said devices comprising a female cutting cylinder and a male cutting cylinder, the latter having a rubber strip, a knife and a stripper. 50

50 44. In combination, feeding apparatus for feeding a continuous web of paper and interlocking devices connected thereto for producing continuously interlocked sheets of paper with the two adjacent edges of two adjacent sheets located in the fold of another sheet, comprising a pair of coöperating interlocking cylinders, each having interrupted folding blades with movable cutting tongues located in the interruptions in the folding blades and gripping jaws, and devices for partially severing sheets from a web of paper and thereafter feeding the web on to the interlocking cylinders, said devices comprising a female cutting cylinder and a male cutting cylinder, the latter having a rubber strip, a knife and a stripper. 55

55 45. In combination, an apparatus for feeding webs of paper, means for alternately partially severing the webs as they are fed, and an interlocking device for said paper adapted to sever fully the partially severed portions. 60

60 46. In combination, an apparatus for feeding webs of paper, means for alternately partially severing the webs as they are fed, and means for severing fully the partially severed portions, and for interlocking the resulting sheets. 65

65 47. A paper folding roll having gripping jaws and folding elements, and paper cutting means located at the same point on the roll as said folding elements. 70

48. In a paper sheet interfolding machine, a folding roll having gripping jaws, means for folding a pair of webs between said jaws, and devices for severing one of said webs at the point where such web is folded within the remaining web while so folded.

49. In a paper sheet interfolding machine, a pair of folding rolls having gripping jaws, means for alternately folding a pair of webs within the jaws of said rolls, and devices for severing each web at the points where such web is folded within the remaining web while so folded.

50. In a paper web interfolding machine, rolls having means for partially severing webs of paper at alternate points along the lengths of said webs, and means for simultaneously folding said sheets at each of the partially severed portions and completely severing the web which has been partially severed at that point.

51. In a paper web interfolding machine, rolls having means for partially severing webs of paper at alternate points along the lengths of said web, folding rolls each having gripping jaws and cutting elements respectively engaging the cutting elements and gripping jaws of the other roll, said cutting elements being positioned to completely sever the web at the points at which it has been partially severed.

52. In a paper web interfolding machine, rolls having means for partially severing webs of paper at alternate points along the lengths of said web, folding rolls each having a gripping jaw and a cutting element respectively engaging the cutting element and gripping jaw of the other roll, and a cutting tongue mounted on each folding roll, said cutting tongues being positioned to completely sever each web at the points at which it has been partially severed.

53. In a paper web interfolding machine, rolls having means for partially severing webs of paper at alternate points along the lengths of said webs, folding rolls each having gripping jaws and cutting elements respectively engaging the cutting elements and gripping jaws of the other roll, cutting tongues mounted on each roll, and means

for moving said tongues to completely sever each web at the points at which it has been partially severed.

54. In combination, feeding apparatus for feeding paper, and interfolding devices connected thereto for producing interfolded sheets of paper, comprising an interfolding cylinder and devices for alternately partially severing sheets from webs of paper, and thereafter feeding the webs on to the 60 interfolding cylinder.

55. In combination, feeding apparatus for feeding a continuous web of paper and interfolding devices connected thereto for producing interfolded sheets of paper, comprising an interfolding cylinder and devices for alternately partially severing sheets from webs of paper and thereafter feeding the webs on to the interfolding cylinder.

56. In combination, feeding apparatus for feeding paper and interfolding devices connected thereto for producing continuously interfolded sheets of paper, comprising an interfolding cylinder and devices for alternately partially severing sheets from webs 75 of paper and thereafter feeding the webs on to the interfolding cylinder.

57. In combination, feeding apparatus for feeding a continuous web of paper and interfolding devices connected thereto for producing continuously interfolded sheets of paper, comprising an interfolding cylinder and devices for alternately partially severing sheets from webs of paper and thereafter feeding the webs on to the interfolding 85 cylinder.

58. In combination, a roll having a cutting element adapted to partially sever a web of paper as it passes from said roll, and a folding roll, having a cutting element 90 adapted to completely sever the web at a point which previously has been partially severed.

In testimony that I claim the foregoing I have hereunto set my hand.

CLYDE E. SWICK.
